TAPE CREEASING APPARATUS

Zell W. Armstrong, Pensacola, Fla.

Application August 4, 1959, Serial No. 831,593

2 Claims. (Cl. 93—84)

This invention relates to an improved apparatus for longitudinally creasing the sheetrock tape used to cover corner joints between wall boards in the so-called "dry wall construction."

In making corner joints between two gypsum-board sheets it is customary to apply cement to the sheets adjacent the joint and to manually longitudinally fold the perforated binding tape, to insert the tape into the corner joint, and to cement the tape on both sides of the angle at the same time. It has proven to be time consuming and difficult for the finisher to manually crease the tape about its central longitudinal axis and consequently various types of tape creasing devices have been developed for use in the trade.

The primary object of the present invention is to provide an improved tape creasing apparatus of sturdy compact construction and especially designed to prevent clogging and jamming of the tape as it is drawn through the creasing means.

A more specific object of the present invention is to provide a tape creasing apparatus which will automatically crease the tape about its central longitudinal axis as the tape is drawn from a supply roll between two elements which are resiliently biased together, one of said elements being a guide block having two angularly converging grooves in one surface thereof and the other of said elements being a cover member pivotally connected at one edge to said guide block for contiguous engagement with the adjacent surface of the guide block.

Other objects and advantages of my invention will become more apparent from a study of the following specification when considered in conjunction with the accompanying drawings in which:

Fig. 1 is a perspective view of the tape creasing apparatus with the tape being fed through the creasing means;

Fig. 2 is a perspective view of the apparatus with the tape being fed in a flat condition through the guide means;

Fig. 3 is a plan view of the apparatus with the cover pivoted to its open position and with the tape removed;

Fig. 4 is an elevational view of the apparatus with the cover in its closed and locked position; and

Figs. 5 and 6 are sectional views taken along lines 5—5 and 6—6 of Fig. 4.

Referring now to the drawings, and more particularly first to Figs. 3 and 4, the tape creasing apparatus consists of a guide block 1 having an inclined upper surface as shown in Fig. 4. Pivoted connected to the guide block 1 by means of hinges 2 is the cover element 3 which is adapted to be swung from an open position (Fig. 3) to a closed position (Fig. 4) extending over the upper surface of the guide block with the lower surface 3a of the cover in contiguous engagement with the upper surface 1a of the guide block.

Secured to the sides of the guide block 1 at the rear end thereof by means of screws 4 is the metal U-shaped bracket 5. Each of the legs 5a, 5b of the U-shaped bracket contains oppositely arranged grooves 6 between

2

which is transversely and removably mounted the spindle 7 of the tape supporting roller 8.

In the upper surface 1a of guide block 1 are two angularly inclined grooves 9 and 10 which form an inverted V-shaped slot in the guide block. As shown in Figs. 3—6, the angle between the grooves 9 and 10 progressively diminishes from approximately 135° at the rear of the guide block to approximately 0° at the front thereof.

Rotatably connected to the rear end surface 1b of the guide block 1 is the guide roller 11. This guide roller 11 is parallel to and spaced from the end surface 1b and is rotatably mounted on the transverse portion of the U-shaped rod 12.

The tape creasing operation of the apparatus may now be readily described.

The tape supporting roller 8 is lifted upwardly until the ends of spindle 7 are removed from slots 6 in the U-shaped bracket 5 and the tape roll 13 is mounted on the tape supporting roller whereupon the ends of the spindle 7 are reinserted into the grooves 6 as shown in Fig. 1.

With the cover 3 in the open position of Fig. 3 the free end 14 of the tape is fed into the grooves 9 and 10 in the upper surface of the guide block. During this initial insertion of the tape into the guide block it may be found to be desirable to manually crease the central longitudinal portion of the tape so that the tape will properly fit into the grooves. The tape will initially enter the guide block 1 at its end surface 1b in a substantially flat state and will be emitted from the front surface 1c of the guide block in a longitudinally creased state with the edges of the tape brought together and the tape folded down the middle as shown in Fig. 1. The cover 3 is then pivoted about hinges 2 to its closed position of Fig. 4 and is resiliently locked in this position by connecting the free end of spring 15 to the locking pin 16 on guide block 1, the other end of spring 15 being permanently connected to the cover 3.

The tape 14 is then drawn through the creasing apparatus as shown in Fig. 1 and is progressively longitudinally creased from its initial flat condition to its final creased condition. The tension spring 15 is self-adjusting and allows the tape to move smoothly through the guide block 1 without any choking or jamming. It is to be noted that the flat under surface 3a of the cover will engage the upper surface of the creased portion of the tape and, due to the action of spring 15, will resiliently bias the folded halves of the tape downwardly into the grooves 9 and 10. Since the depth of each groove 50 is approximately equal to half the width of the tape, the tape will be automatically creased about its central longitudinal axis as it is drawn through the creasing means.

The creasing apparatus may be removably connected to the flat upper top member 17 of step ladder 18 by means of the spring 19. One end of the spring 19 is fixedly secured to the bottom surface of guide block 1 by means of eyelet 20 while the other end of the spring is removably connected to the pin 21 on the guide block. Thus to secure the tape creasing apparatus to the ladder, 60 the guide block 1 is placed on the top step 17 and the spring 19 is brought beneath the step and secured under tension to the pin 21.

The user of the apparatus may then stand on the step ladder and withdraw a desired length of tape from the roll 13 through the creasing or guide block 1 and then tear off the length of creased tape for application to the wall-to-wall or ceiling-to-wall right angled joint.

Should it be desired to withdraw the tape from the roll 13 in a flat state for certain applications, such as in 70 finishing a butt joint between two coplanar sheets, instead of feeding the tape through the grooves 9, 10 in the guide block 1 the tape end 14 may be brought under the

guide roller 11 and between the roller 11 and the rear surface 1b of the guide block 1 as shown in Fig. 2. The user of the apparatus may then tear off the desired length of tape in its flat condition and apply the same directly to the installation.

While in accordance with the patent statutes I have illustrated and described the best embodiment of my invention now known to me, it will be apparent to those skilled in the art that other changes and embodiments may be made in the apparatus described without deviating from my invention as set forth in the following claims.

I claim:

1. Apparatus for longitudinally creasing a strip of flat tape comprising a guide block having a flat upper surface containing a pair of longitudinally-extending angularly-arranged grooves of equal depth therein, said grooves being arranged in transverse cross-section of the block in an inverted V-shaped configuration, said grooves forming at a first end of the guide block an obtuse angle and progressively converging to form an acute angle adjacent the other end of the guide block, a cover element above the guide block and having a flat lower surface, and means resiliently biasing the cover element into engagement with the guide block whereby the tape will be progressively formed from a substantially flat condition to a longitudinally-creased state as it is drawn through the guide block from the first end to the other end thereof.

2. Apparatus for longitudinally creasing flat tape as it is removed from a roll thereof comprising a guide block having a flat upper surface, a U-shaped bracket rigidly

connected at the extremities of the legs thereof to the sides of said guide block and extending outwardly from one end thereof, a tape supporting roller removably connected between the legs of said bracket, a cover element pivotally connected at one edge to one side edge of the upper surface of the guide block, said cover element having a flat lower surface which contiguously engages the upper surface of the guide block when the cover element is pivoted to a closed position over the guide block, and means resiliently biasing the cover element into engagement with the flat upper surface of the guide block, said guide block having in the upper surface thereof a pair of grooves of uniform depth extending longitudinally of the guide block and arranged in transverse cross-section of the block in an inverted V-shaped configuration, said grooves forming at the end of the guide block adjacent the U-shaped bracket an obtuse angle and progressively converging to form an acute angle adjacent the other end of the guide block so that the tape will be progressively formed from a flat condition to a longitudinally-creased state as it is fed from a roll of tape mounted on said tape supporting roller through the guide block grooves.
